UNITED STATES PATENT OFFICE.

LUKE TOZER, OF IOLA, KANSAS.

OIL-BURNER.

1,081,994.

Specification of Letters Patent. Patented Dec. 23, 1913.

Application filed August 18, 1913. Serial No. 785,266.

To all whom it may concern:

Be it known that I, LUKE TOZER, a citizen of the United States, residing at Iola, in the county of Allen and State of Kansas, have invented certain new and useful Improvements in Oil-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to oil burners, and more particularly to a burner of that class adapted for use in stoves or furnaces, and wherein fuel oil is converted into gas and mixed with air to provide a combustible fuel; the principal object of the invention being to provide a burner wherein the oil vapor or gas and oxygen may be properly mixed and delivered from the burner in a manner to secure the highest efficiency.

20 25 It is also an object of the invention to provide the burner with a cleaning element whereby carbon or other solid matter ordinarily carried in suspension in the liquid oil and freed therefrom when the oil is transformed into vapor or gas, may be removed from the burner while the latter is in operation, and thereby constantly maintain the burner in operative condition, and obviate the necessity of shutting off the fire.

30 35 In the accompanying drawings I have illustrated a preferred form of structure embodying the features of the invention, wherein:—

40 45 Figure I is a vertical section of a fire bowl of an ordinary stove or furnace equipped with my improved oil burner; the latter being shown in elevation. Fig. II is a similar view with the burner parts in vertical section. Fig. III is a horizontal section on the line III—III, Fig. II. Fig. IV is a detail perspective of a generator. Fig. V is a plan view of the base plate.

50 Referring more in detail to the parts:— Fig. 1 designates the fire bowl of an ordinary stove or furnace, which is here illustrated merely to show the combination and mounting of my improved burner with a stove or furnace structure.

55 Seated on a flange 2 which surrounds the grate opening of the fire bowl is a base

plate 3 having a central aperture 4, divided by a cross bar 5 that is provided with a central threaded aperture 6; the upper face of the base having an upturned flange 7 surrounding the central aperture 4.

Seated on the base 3 is a bowl-shaped member 9 having a base flange 10 located within and confined by the upstanding flange 7 of the base plate 3 and having a rim 10' forming an annular chamber 11, and having an interior wall 12 converging upwardly from the edge of the base aperture 4 to the top of the body of the bowl.

Located within the chamber formed by the tapered wall 12 is a barrel 13 having a reduced stem 14 threaded into the aperture 6 in the cross bar of the bowl base, and provided with a T-union 15, having lateral connection with an oil supply pipe 16 and having a plug 17 in its lower end adapted for removal when the barrel is to be cleaned; the reduction of the barrel forming a seat 18 whereby the barrel is supported on the cross bar 5.

Integral with the upper end of the barrel 13 are bosses 20 having lower portions 21 adapted for bearing against the inner face of the bowl to space the barrel therefrom and provide a port or mouth through which free air taken in through the bowl base may be delivered for mixture with fuel gas or vapor, and having outstanding upper ends 22 seated on the upper edge of the bowl to space the generating cup 23, which is formed integral with the barrel, from the top of the bowl 9, and thereby provide a laterally opening port between the top of the bowl and the under face of the cup, through which the free air may pass after being delivered from the interior of the bowl.

The generator cup 23 comprises a cupped upper face 24 communicating with the interior of the barrel 13, and a depending edge flange 25 which is adapted for partially confining the free air delivered up through the interior of the bowl 9, so that the air may be thoroughly distributed to insure proper mixture with the fuel gas or vapor before ignition.

Supported on, and depending about, the generator cup 23, is a cap 26, the base of which is provided with bosses 27 adapted to bear against the upper edge of the cup to space the cap therefrom, and thereby provide a port through which the fuel gas gen-

erated in the cup may pass, and the sides of which are spaced from the sides of the cup by ribs 28 on the latter, in order that the fuel gas passing through the top ports may be delivered downwardly about the generator, the lower edge of the cap being extended below the upper edge of the bowl 9, so that both the fuel gas or vapor and the free air are confined together before being released from beneath the cap, in order to secure a suitable mixture of such elements.

The generator barrel 13 has a bore 29 leading down from the base of the cup 24 to a seat 30, which is preferably located above the reduced portion 14, and communicates with a reduced bore 31 into which the liquid oil is delivered from the supply pipe 16.

The seat 30 is provided for supporting a cleaner 32, preferably comprising an inverted cone-shaped coil 33, formed of wire, and having a shank 34 extended past the top of the bore, where it is provided with a ring 35, whereby the cleaner may be lifted when it is to be removed; the shank 34 being preferably extended through the body of the cone-shaped coil 33 to the base thereof, in order that the coil may be lifted from the bottom and thereby obviate distortion thereof. The cap 26 is also preferably provided with a ring 36 whereby it may be removed from the generator cup by means of a hook, or the like, when the burner is to be cleaned, or for any purpose.

35 In using the burner, presuming the parts to be constructed and assembled as described, oil is delivered into the reduced portion of the generator barrel and flows up through the bores in the barrel to the cup 24. When 40 the oil is first turned on it rises into the generator cup and overflows the edges thereof into the bowl 11, where it may be ignited to heat the parts and generate vapor from the incoming oil.

45 When the parts have been sufficiently heated to generate vapor in the cup 24 this vapor is conducted through the annular channel between the cup and cap, and past the port between the cup and the top of the 50 interior wall, where it mixes with free air that enters through the base of the fire bowl and is conducted to the annular chamber and within the cap; the mixture of vapor and free air forming a combustible fuel which 55 burns upon delivery from beneath the edge of the cap.

It has been found from experience that most fuel oil contains carbon or solid matter in suspension, which is freed when the liquid 60 is vaporized, and, being heavier than the oil, will drop through the oil that rises in the vertical generator bore.

In order to obviate stoppage of the barrel, I have provided the cleaner, herein illustrated, and mount same as described and

shown, so that the carbon dropping through the generator barrel and cleaner coil will lodge in the bottom of the coil, so that when the cleaner is lifted out of the barrel the carbon is removed therewith.

It is apparent that with the present construction, the cap 26 may be removed and the cleaner lifted from the generator barrel without extinguishing the burner, so that the cleaning may be effected much more easily and quickly than with a burner which it is necessary to dismantle entirely in order to remove the carbon or other solid matter.

Having thus described my invention, what I claim as new therein, and desire to secure by Letters Patent, is:—

1. In an oil burner, the combination with a generator, of a supply conduit leading to the generator, and a cleaner located in said conduit, and comprising a cone-shaped coil.

2. In an oil burner, the combination with a generator, of a supply conduit leading to the generator, and a cleaner located in said conduit, comprising a cone-shaped coil, and having a shank leading into said generator.

3. In an oil burner, the combination with a generator having a supply conduit leading upwardly thereto, and a cleaner located within said conduit and comprising an inverted cone-shaped coil, having a shank projecting upwardly through the conduit and terminating in a handle portion within the generator.

4. In an oil burner, a generator comprising a depending barrel having a reduced lower portion providing a seat, and a cleaner comprising an inverted coil supported on said seat, and having a shank extending through the barrel into the upper portion of the generator.

5. In an oil burner, a generator comprising a cupped upper portion, and a depending barrel having a reduced lower end forming an interior seat, and a cleaner comprising an inverted cone-shaped coil of wire supported on said seat, and having a shank extending upwardly and having a ring at its upper end located within the cupped portion of the generator.

6. In an oil burner, a generator comprising a cupped upper portion, and a depending barrel having a reduced lower end forming an interior seat, and a cleaner comprising an inverted cone-shaped coil of wire supported on said seat and having a shank extended upwardly through the coil and projecting into the cupped upper portion of the generator.

7. An oil burner comprising a bowl, having an upwardly converging interior wall forming a tapered channel within the bowl, a generator comprising a cupped upper portion, and having a barrel located within said tapered channel, bosses integral with and supporting the generator on the upper edge

- of said wall, and spacing same from said wall, and a cap supported on the cupped upper portion of the generator and spaced vertically and laterally therefrom.
- 5 8. An oil burner comprising a bowl having an interior wall forming a central channel therethrough, a generator comprising a body portion having a cupped upper portion and a downwardly extending barrel of 10 less diameter than the body portion, bosses integral with the barrel and body portion of the generator and provided with shoulders for supporting the generator on the interior wall of said bowl and spacing the 15 barrel inwardly and the body portion upwardly from said wall, and a cap covering the top and sides of said generator.
9. An oil burner comprising a bowl having an interior wall forming a central channel therethrough, a generator comprising a body portion having a cupped upper portion and a downwardly extending barrel of 20 less diameter than the body portion, bosses integral with the barrel and body portion 25 of the generator and provided with shoulders for supporting the generator on the in-
- terior wall of said bowl and spacing the barrel inwardly and the body portion upwardly from said wall, and a cap covering the top and sides of said generator and depending into said bowl.
10. In an oil burner, the combination with a bowl having a tapered interior wall forming a central channel through the bowl, a generator comprising a body portion having a cupped upper face, and having vertical ribs on its periphery, a barrel integral with and depending from said body portion into the bowl channel, bosses integral with said barrel and body portion for supporting the generator and spacing the barrel from said bowl, and a cap supported on said generator and having interior bosses for spacing the head of the cap from the upper edge of the body portion, substantially as set forth.
- In testimony whereof I affix my signature in presence of two witnesses.
- LUKE TOZER.
